UNITED STATES PATENT OFFICE.

BENJAMIN H. ANIBAL, OF HIGHLAND PARK, MICHIGAN, ASSIGNOR TO GENERAL MOTORS CORPORATION, OF DETROIT, MICHIGAN, A CORPORATION OF DELAWARE.

DESIGN FOR AN INSTRUMENT-BOARD FOR MOTOR-VEHICLES.

58,532.

Specification for Design.

Patented Aug. 2, 1921.

Application filed April 7, 1921. Serial No. 459,479. Term of patent 14 years.

To all whom it may concern:

Be it known that I, BENJAMIN H. ANIBAL, a citizen of the United States, residing at Highland Park, county of Wayne, State of Michigan, have invented a new, original, and ornamental Design for an Instrument-Board for Motor-Vehicles, of which the following is a specification, reference being had to the accompanying drawing, forming a part thereof.

The drawing shows my design for instrument board for motor vehicles, in front elevation.

I claim:

The ornamental design for an instrument board for motor vehicles illustrated in the accompanying drawing.

BENJAMIN H. ANIBAL.
